UNITED STATES PATENT OFFICE.

LIZZIE M. KEIGHER, OF NEWARK, NEW JERSEY.

DESIGN FOR A FANCY DRESS ORNAMENT.

SPECIFICATION forming part of Design No. 36,664, dated December 1, 1903.

Application filed October 14, 1903. Serial No. 177,080. Term of patent 7 years.

To all whom it may concern:

Be it known that I, LIZZIE M. KEIGHER, a citizen of the United States, residing at Newark, in the county of Essex and State of New Jersey, have invented a new, original, and ornamental Design for Fancy Dress Ornaments, of which the following is a specification, reference being had to the accompanying drawing, forming a part thereof.

The single figure of the accompanying drawing shows in plan fancy dress ornaments of my new design for ladies' and children's dresses and illustrates the invention fully and clearly.

What I claim as new is—15 The ornamental design for a fancy dress ornament, as shown.

LIZZIE M. KEIGHER.
